ELASTIC FABRIC

Filed Dec. 23, 1935

FIG. 1.

FIG. 2.

INVENTOR:
Clarence D. Maurer,
BY *Fred C. Schuler,*
ATTORNEY.

UNITED STATES PATENT OFFICE

98,483

DESIGN FOR AN ELASTIC FABRIC

Clarence D. Maurer, West Reading, Pa., assignor
to The Narrow Fabric Company, West Reading,
Pa., a corporation of Pennsylvania

Application December 23, 1935, Serial No. 60,234

Term of patent 14 years

To all whom it may concern:

Be it known that I, Clarence D. Maurer, a citizen of the United States of America, residing at West Reading, in the county of Berks and State of Pennsylvania, have invented a new, original, and ornamental Design for an Elastic Fabric, of which the following is a specification, reference being had to the accompanying drawing, forming part thereof.

Figure 1 discloses a portion of elastic fabric embodying my ornamental design, to which no tension is applied.

Fig. 2 discloses a portion of elastic fabric em-

bodying my ornamental design, as it appears when subjected to tension substantially equivalent to that incident to normal usage.

The figures disclose the elastic fabric enlarged to approximately one and one-half times normal size, but which will approximate full size upon the reduction of the same for printing.

I claim:

The ornamental design for an elastic fabric as shown and described.

In testimony whereof I affix my signature.

CLARENCE D. MAURER.
